D. H. WOLFE

METHOD AND APPARATUS FOR GROOVING AND FLANGING TUG RIMS

Filed July 14 1926

UNITED STATES PATENT OFFICE.

DELL H. WOLFE, OF PARKERSBURG, WEST VIRGINIA, ASSIGNOR TO THE PARKERSBURG RIG & REEL COMPANY, OF PARKERSBURG, WEST VIRGINIA, A CORPORATION OF WEST VIRGINIA.

METHOD AND APPARATUS FOR GROOVING AND FLANGING TUG RIMS.

Application filed July 14, 1926. Serial No. 122,448.

This invention relates to a method and apparatus for grooving and flanging tug rims used in connection with oil well drilling apparatus.

5 Standard tug rims are formed of relatively heavy sheet metal and are provided in their peripheries with a plurality of circumferential grooves in which the cables are adapted to run, the rims further being provided at their ends with inwardly turned substantially radial flanges. The grooves and flanges referred to usually are formed by two separate operations, the grooves initially being formed by one rolling operation, 10 after which the rims are transferred to a second machine which is adapted to form the flanges. It will be obvious that much labor is involved and much time is lost in transferring the rims from one machine to another. 15 It has been proposed to perform both operations on the same machine, but heretofore this has been accomplished by rolling the grooves and then changing the rolls of the machine to form the flanges.

20 An important object of the present invention is to provide a novel method of forming the grooves and flanges referred to.

A further object is to provide a novel method of providing tug rims with grooves 25 and flanges on a single machine without requiring the removal and replacing of rolls.

A further object is to provide a method of the above mentioned character wherein a pair of grooving rolls are adapted to receive 30 the tug rim therebetween and to provide flanging rolls which are adapted to center the rims with respect to the grooving rolls during the rolling operation, after which the rims are retained in position by the 35 grooving rolls during the flanging operation.

A further object is to provide an apparatus for carrying out the method referred to wherein there is provided a pair of coacting 40 grooving rolls mounted upon parallel shafts and adapted to receive a tug rim therebetween whereupon movement of the shafts toward each other and rotation of the rolls is adapted to form the grooves, 45 flanging rolls being provided for initially centering the rim with respect to the grooving rolls and for forming the flanges after the grooves have been completed.

A further object is to provide an apparatus of the above mentioned character 55 wherein one of the shafts is provided on opposite sides of the roll thereon with flanging rolls which are slidable upon the shaft, outward movement of the flanging rolls being limited whereby the space therebetween 60 is equal to the width of a tug rim blank, so that the latter will be maintained properly centered during the grooving operation.

A further object is to provide an apparatus of the character just mentioned where- 65 in the flanging rolls are adapted to be moved inwardly and clamped in operative position to permit the flanging operation to take place.

Other objects and advantages of the in- 70 vention will become apparent during the course of the following description.

In the drawings I have shown one embodiment of the invention. In this show- 75 ing,

Figure 1 is a side elevation of the rolling mechanism showing a tug rim blank in position for the initial operation,

Figure 2 is a similar view showing the completion of the grooving operation,

Figure 3 is a section on line 3—3 of Figure 2, showing the beginning of the flanging operation, and,

Figure 4 is a view similar to Figure 2 showing the completion of the flanging op- 85 eration.

Referring to the drawings the numerals 10 and 11 designate a pair of suitable shafts each having a reduced portion 12 providing a shoulder 13. The reduced portion of 90 each shaft is provided with a key 14 for a purpose to be described. Outwardly of the reduced portion 12, each shaft is provided with a threaded portion 15 upon which is mounted a nut 16, the inner face 17 of each 95 nut constituting a shoulder adapted to coact with each shoulder 13, for a purpose to be described.

The lower shaft 11 is provided with a grooving roll 18 having peripheral grooves 100 19 therein. The roll 19 is centered between the shoulders 13 and 17 and is maintained in position by suitable spacing washers 20. It will be apparent that the roll 18 is fixed against longitudinal movement with respect 105 to the shaft 11. A coacting roll 21 is ar-

ranged on the reduced portion 12 of the shaft 10, this roll being provided with peripheral ridges 22 corresponding in position to the grooves 19 of the roll 18. The 5 roll 21 is fixed in a central position between the shoulders 13 and 17 by the key 14. A pair of flanging rolls 23 are arranged outwardly of the roll 21 and surround the reduced portion 12 of the shaft 10. The rolls 10 23 are adapted to slide toward and away from the roll 21, the key 14 forming a spline connection between the rolls 23 and the shaft 10. Each flanging roll is provided with a flat inner face 24 and an inclined outer face 15 25 for a purpose to be described. It will be apparent that the outer faces of the rolls 23 are adapted to contact with the shoulders 13 and 17 to limit the outward movement of the rolls. A bolt 26 is arranged on each side of 20 the shaft 10 and is carried by one of the rolls 23. These bolts slidably extend through the roll 21, and the other roll 23, and the bolts are threaded at their outer ends as at 27 to be received in nuts 28, as shown in Figure 4.

25 Referring to Figure 1, the numeral 29 designates a tug rim blank which is substantially cylindrical as will be apparent. The width of the rim is equal to the distance between the inner faces of the flanging rolls 23 whereby it will be obvious that the tug rim 30 blank will be centered between the flanging rolls and with respect to the rolls 18 and 21. In Figure 2 of the drawings the rim 29 is shown after the completion of the grooving 35 operation, the rim being provided with cable receiving grooves 30. The grooving operation, to be described, causes some of the portions of the metal of the tug rim to be stretched outwardly while the grooved portions 40 are compressed inwardly. The edges of the rim retain their normal size, and accordingly the outer portions of the rim will be inclined or tapered as indicated at 31. The portions 31 are adapted to be bent inwardly by the flanging operation as indicated at 32 in Figure 4.

45 The operation of the apparatus is as follows:

The shafts 10 and 11 are supported in any 50 suitable forms of bearings and are adapted to be moved toward each other in the usual manner to permit the rolling operations to take place as will be apparent, and any suitable means may be employed for rotating the shafts. When it is desired to form a tug 55 rim, the shafts 10 and 11 are moved apart a sufficient distance to permit a blank rim to be placed in position. The flanging rolls 23 are moved outwardly to the limit of their 60 movement, whereupon the shafts 10 and 11 are slowly brought together to the position indicated in Figure 1, the tug rim being arranged with its edges between the faces 24 of the flanging rolls 23. The shafts 10 65 and 11 are then revolved and are moved to-

ward each other, whereupon the grooves 30 will be formed. It will be apparent that the flanging rolls act as guides to maintain the tug rim in proper position during the initial grooving operation. Upon completion of 70 the grooving operation, the shafts are then moved apart and the flanging rolls are moved inwardly to contact with the roll 21, whereupon the nuts 28 are applied to the bolts 26 to secure the flanging rolls in position. It will be apparent that the grooves 19 of the roll 18 are adapted to maintain the tug rim in position while the flanging rolls are being secured in operative position as described. The shafts 10 and 11 are then 75 moved toward each other to the position shown in Figure 3 whereupon the tapered faces 25 of the flanging rolls contact with the tapered portions 31 of the tug rim formed during the grooving operation. Continued movement of the shafts toward each other will then cause the flanging rolls to force the outer portions of the rim inwardly to form the finished flanges 32.

80 While I have described bolts for securing the flanging rolls in position, it will be apparent that any suitable fastening means may be employed, and that if desired, means may be provided for positively holding the flanging rolls 23 in their outer positions.

85 From the foregoing, it will be apparent that I provide a method of forming tug rims wherein the two operations expeditiously may be carried out on a single machine without changing the rolls, and wherein the 100 flanging rolls act as guide means to start the grooving operation, while one of the flanging rolls acts as a guide during the flanging operation.

90 It is to be understood that the form of 105 the invention herewith shown and described is to be taken as a preferred example of the same and that various changes in the shape, size and arrangement of parts may be resorted to without departing from the spirit 110 of the invention or the scope of the subjoined claims.

I claim:

1. The method of forming metal rims 115 which consists in arranging a blank rim between a pair of grooving rolls with its edges between a pair of flanging rolls to be guided thereby, moving the grooving rolls toward each other and revolving at least one of them to form a peripheral groove in the 120 rim, then forming flanges at the edge portions of the rim with said flanging rolls.

2. The method of forming metal rims 125 which consists in arranging a blank rim between a pair of grooving rolls with its edges between a pair of flanging rolls to be guided thereby, moving the grooving rolls toward each other and revolving at least one of them to form a peripheral groove in the rim, leaving the grooved rim in position on one 130

of said grooving rolls to be guided thereby, and rolling flanges at the edge portions of the rim with said flanging rolls.

3. The method of forming metal rims which consists in arranging a blank rim between a pair of grooving rolls with its edges between a pair of flanging rolls to be guided thereby, moving the grooving rolls toward each other and revolving at least one of them to form a peripheral groove in the rim, leaving the rim in position on one of said grooving rolls to be guided thereby, moving the flanging rolls away from the rim and then toward each other, and then 10 rotating the flanging rolls and moving them into contact with the rim to form flanges at the edge portions thereof.

4. Apparatus of the character described comprising a pair of shafts adapted to be rotated and moved toward and away from each other, coacting grooving rolls carried by said shafts, and a pair of supplementary rolls arranged outwardly of said grooving rolls and movable toward and away from 20 said grooving rolls.

5. Apparatus of the character described comprising a pair of parallel shafts adapted to be rotated and moved toward and away from each other, coacting grooving rolls carried by said shafts, and a pair of supplementary rolls slidably mounted on one of said shafts outwardly of said grooving rolls and movable toward and away from each 30 other.

6. Apparatus of the character described comprising a pair of parallel shafts adapted to be rotated and moved toward and away from each other, coacting grooving rolls carried by said shafts, and a pair of supplementary rolls slidably mounted on one of 35

said shafts outwardly of said grooving rolls and movable toward and away from each other, said second named rolls being movable inwardly to contact with said grooving rolls, said last named shaft being provided 45 with means for limiting the outward movement of said supplementary rolls.

7. Apparatus of the character described comprising a pair of parallel shafts adapted to be rotated and moved toward and away from each other, a grooving roll carried by each of said shafts, and a pair of flanging rolls mounted upon one of said shafts outwardly of the grooving roll thereon, said flanging rolls being slidable on said shaft 50 toward and away from said last mentioned grooving roll and provided with tapered outer faces, said last mentioned shaft being provided with means for limiting the outward movement of said flanging rolls. 55

8. Apparatus of the character described comprising a pair of parallel shafts adapted to be rotated and moved toward and away from each other, a grooving roll carried by one of said shafts, the other of said shafts 60 being provided with a reduced portion forming a shoulder, a coacting grooving roll carried by said second named shaft centrally of the reduced portion thereof, the outer end of said last named shaft being provided 65 with a coacting shoulder, and a flanging roll slidable on the reduced portion of said last named shaft on each side of the grooving roll thereon, each of said flanging rolls having a tapered outer face and having its outward movement limited by one of said shoulders. 70

In testimony whereof I affix my signature.

DELL H. WOLFE.
